[57] CLAIM

The ornamental design for stand for a nursery mobile, as shown and described.

DESCRIPTION

FIG. 1 is a rear perspective view of a stand for a nursery mobile showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear perspective view of a second embodiment of FIG. 1, the difference residing in the wall mounting means;

FIG. 9 is a left side elevational view of the wall mounting means, shown separately for clarity of illustration;

FIG. 10 is a right side elevational view of FIG. 9;

FIG. 11 is a rear elevational view of FIG. 9;

FIG. 12 is a front elevational view of FIG. 9;

FIG. 13 is a top plan view of FIG. 9; and,

FIG. 14 is a bottom plan view of FIG. 9.
